UNITED STATES PATENT OFFICE.

HERMAN K. ANSINGH, OF MURRYSVILLE, PENNSYLVANIA, ASSIGNOR TO WESTINGHOUSE ELECTRIC & MANUFACTURING COMPANY, A CORPORATION OF PENNSYLVANIA.

HOUSING FOR METERING EQUIPMENT.

Application filed July 27, 1922. Serial No. 577,834.

My invention relates to outdoor transformer housings and particularly to housings for containing current and voltage transformers used in connection with watt-hour meters installed in outdoor current-distributing systems.

Heretofore, it has been customary, in certain classes of outdoor distributing systems, to place the current and voltage transformers and fuses used in connection with watt-hour meters in housings having bottom, top, rear and side walls and open fronts that are closed by doors that may be pivoted either to the tops of the housings or to the bottoms or the side walls thereof.

In order to provide ample space for the equipments within the housings, it is necessary to make the housings of ample depth. The voltage transformers are usually secured to the rear walls of the housings and, consequently are located at considerable distances from the fronts thereof and are relatively inaccessible for the purpose of inspection and repair. This difficulty is also experienced in gaining access to the current transformers which are usually mounted upon the top or the rear walls of the housings.

One object of my invention is to provide a housing wherein rear and top walls are joined to constitute a support for the voltage transformer and the current transformer, respectively, and wherein the bottom wall, side walls and front wall constitute a cover for the apparatus, the cover being hinged to the lower portion of the rear wall in such manner that it may be dropped away therefrom to expose the front, bottom and sides of the apparatus. By reason of this construction, access may be had to the apparatus within the housing from the sides, front and bottom thereof, thus facilitating the inspection, replacement and repair of the apparatus.

Another object of my invention is to provide a housing that may be constructed of sheet metal and which is relatively inexpensive to manufacture.

Another object of my invention is to provide a housing of the character above described that is provided with a simple and effective means for retaining the cover in closed position.

These and other objects, that will be made

apparent throughout the further description of my invention, are attained by means of the apparatus hereinafter described, and illustrated in the accompanying drawings, wherein:

Figure 1 is a perspective view of the transformer housing;

Fig. 2 is a vertical section through the housing, showing the cover in closed position; and

Fig. 3 is a front elevation of the apparatus shown in Fig. 2, showing the cover removed.

Referring to the drawings, the apparatus includes an instrument-supporting portion 4 constituting a rear wall 5 and a top wall 6 of the housing, and a cover portion 7 constituting side walls 8, a front wall 9 and a bottom wall 10 of the housing. The supporting portion 4 is made of a single sheet of metal that is bent to form the rear and top walls and to provide flanges 11 along the edges of the plate. The outer end of the top wall 6 is supported by diagonal braces 12 that are connected to the flanges 11 near the outer edge of the top wall and to the flanges 11 adjacent to the lower edge of the rear wall 5.

The cover portion 7 is made of sheet metal suitably flanged and overlapped at adjacent corners to constitute a rigid box-like structure. The cover 7 is hinged to the rear wall 5 by means of a bolt 13 that extends through both of the flanges 11 on the rear wall, as indicated in the drawings. A tubular spacing member 14 is mounted upon the bolt 13 and serves to prevent inward movement of the side walls 8 of the cover.

The flanges 11 of the rear wall 5 are provided with clips 15 made of standard angle iron and perforated to receive attaching bolts 16 by means of which the housing is secured to cross arms 17 that are mounted upon the pole for supporting the transformer housing.

The outer edge of the front wall 9 is provided with a flange 18 made of standard angle iron. Threaded bolts 19 are permanently secured to the flange 18 and are provided with wing nuts 21 which serve to retain the cover in closed position. When the cover is moved to closed position, the bolts 19 enter the slots 22 cut in the free edge of the top wall 6, and the nuts 21 are then se-

cured upon the outer face of the top wall. This construction constitutes a simple, effective and inexpensive means for securing the cover in closed position.

5 As indicated in Figs. 2 and 3, the current transformers 23 are attached to the top wall 6 in the usual manner. The top wall is provided with openings 24 through which insulator bushings 25 extend into the housing. 10 Series transformers 26 and fuses 27 are secured to the rear wall 5 by brackets 28.

When the cover is dropped to its open position, as indicated in Fig. 1, it will be seen that the transformer and fuse apparatus is 15 readily accessible from four sides of the housing and may readily be inspected or repaired without interference of the side and bottom walls.

It will be seen that the side walls 8 are mounted within the flanges 11 and that the flanges 11 are continuous from the lower extremity of the rear wall to the outer extremity of the top wall. The flange 11 overlaps the edges of the cover and prevents the entrance of moisture into the housing. The side walls 8 are reinforced by standard angle-iron bars 29 which increase the rigidity of the cover structure.

While I have described and illustrated but 30 out embodiment of my invention, it will be apparent to those skilled in the art that various changes, modifications, substitutions, additions and omissions may be made in the apparatus illustrated without departing 35 from the spirit and scope of my invention, as set forth in the appended claims.

I claim as my invention:

1. In an instrument housing, a pair of angularly disposed instrument-supporting wall members comprising the rear and top walls 40 of the housing and constituting a fixed housing portion open at the sides, front and bottom, and a movable cover portion pivoted to the rear wall and constituting front, bottom 45 and side walls of the housing.

2. In an instrument housing, a pair of angularly disposed instrument-supporting wall members comprising rear and top walls 50 of the housing and constituting a fixed housing portion open at the sides, front and bottom, means whereby the wall members may be attached to a support, and a cover portion hinged to the rear wall and constituting front, bottom and side walls of the housing 55 and movable to open position wherein access

may be had to the instrument from the sides, front and bottom of the housing.

3. In an instrument housing, a pair of angularly disposed instrument-supporting wall members comprising rear and top wall members 60 of the housing and constituting a fixed housing portion open at the sides, front and bottom, means whereby the wall members may be attached to a support, braces connecting the free end of the top wall and the 65 lower portion of the rear wall for preventing displacement of the top wall, and a cover portion hinged to the rear wall and constituting front, bottom and side walls of the 70 housing.

4. In an instrument housing, a pair of angularly disposed instrument-supporting wall members comprising rear and top wall members 75 of the housing and constituting a fixed housing portion open at the sides, front and bottom, means whereby the wall members may be attached to a support, braces connecting the free end of the top wall and the lower portion of the rear wall for preventing displacement of the top wall, a cover portion 80 hinged to the rear wall and constituting front, bottom and side walls of the housing and releasable means for retaining the cover in closed position.

5. In an instrument housing, a pair of angularly disposed instrument-supporting wall members comprising the rear and top walls 85 of the housing and constituting a fixed housing portion open at the sides, front and bottom, a cover portion pivoted to the rear wall 90 and constituting front, bottom and side walls of the housing and adapted to be retained in open position by force of gravity and means for releasably retaining the cover in closed 95 position.

6. In an instrument housing, a pair of angularly disposed instrument-supporting wall members comprising the rear and top walls of the housing and constituting a fixed housing portion open at the sides, front and bottom, 100 the free edge of the top wall being provided with slots, a cover portion pivoted to the rear wall and constituting front, bottom and side walls, and adjustable means on the cover member adapted to enter the said slots when 105 the cover is in closed position for retaining the cover in closed position.

In testimony whereof, I have hereunto subscribed my name this 10th day of July, 1922.

HERMAN K. ANSINGH.
